FREDERICK W. VICKERY, OF LONDON, ENGLAND, ASSIGNOR TO VICKERY LIMITED, OF BOSTON, MASSACHUSETTS.

FELT-CLEANING MACHINE.

Application filed October 22, 1926, Serial No. 143,492, and in Austria July 13, 1925.

This invention relates to an improved process for cleaning the felt belts of paper making machines and to mechanisms for carrying the said process into practical operation.

The invention is particularly adapted to be used in connection with the cleaning of felt belts for paper making machines, as for example, cylinder machines, in which 10 the stock is picked up by the felt in a very wet condition, and the felt needs to be thoroughly cleaned or washed to remove from it the short fibers, coloring and loading matter which adhere to it during the 15 process of removing fluid from the paper stock.

In cleaning felt belts of the character set forth a very abundant washing is needed in order to satisfactorily clean the felt, and the 20 principal object of this invention is to effect the desired results with a minimum water consumption and pumping power.

The process whereby this object is attained consists in forcing cleaning fluid 25 against one or both faces of the felt which is being cleaned, confining the fluid to a restricted area of the felt and holding it pressed against the surface of the felt which is being cleaned. Preferably, the fluid thus 30 forced against the felt is moved in a direction opposite to that in which the felt is moving. The fluid is preferably forced against and along the felt by a plurality of jets under pressure, the ends of the nozzles 35 which supply the jets being preferably positioned so as to direct the fluid at an angle against the felt in the opposite direction to which the felt is travelling and at a sufficient distance from the surface of the 40 felt so that the vena contracta of each of the jets shall be at the face of the felt. A quantity of cleaning fluid under pressure travelling in the opposite direction to that of the travel of the felt is thus obtained constituting a current or currents of fluid under pressure, so directed and confined as to exert pressure upon and along the surface 45 or surfaces of a moving felt belt and subjecting the same to a pressure scrubbing operation by reason of the relative movement of the felt and fluid. The current of fluid 50 may carry with it bubbles of air, causing a somewhat aerated condition.

The term "fluid" is used throughout the specification and claims in a generic sense to include a liquid, gas or vapor, and the term "suction" includes any means of varying the air pressure on the belt.

As an additional cleansing means, steam may be introduced to heat the fluid flowing 60 along in contact with the felt and under pressure.

The jets of cleaning fluid, positioned as aforesaid, deliver a blow upon the felt, which materially contributes to dislodge 65 the matter to be removed, and to make the impact as forceful as possible the jets are positioned as aforesaid, with the vena contracta of the jets at the face of the felt.

In order to still more thoroughly clean 70 the felt belt under the most advantageous condition, the felt is preferably locally tensioned along the area where the cleaning fluid is operating thereon, and this is preferably accomplished by means of a plate 75 which is pressed into contact with the undersurface of the felt and is preferably held thereagainst with a yielding pressure, the said plate being provided with ridges on its opposite edges extending longitudinally of 80 the felt in order to assist in confining the cleaning fluid to a restricted area under pressure. The pressure of the fluid against the face of the felt belt is thus obtained by the combined action of the pressure plates 85 and the current of fluid under pressure, the pressure upon the fluid being such that it is able to overcome any frictional resistance of the plates and of the felt and still be able to flow out at the opposite end of the plates 90 to which it is delivered, at an appreciable rate of flow.

In this operation of a process wherein a fluid moving under pressure along the surface of the felt is obtained, each cubic unit 95 of fluid will be brought into contact with a great many square units of the face of the felt and the fluid will be followed, as it flows along the felt, by other units of fluid, under pressure which, impinging 100 upon the working surface of the felt, will dislodge mechanically, particles adhering thereto. It will thus be seen that this portion of the felt cleaning process has the advantage of utilizing the same fluid over a 105 considerable number of units of area, re-

quiring, therefore, comparatively only a small amount of pumping power and of cleaning fluid, while effecting a very complete cleansing of the surface of the felt 5 which is being operated upon.

It will be understood that as the felt is being cleaned, in a manner hereinbefore set forth, the surface of the felt with the foreign particles thereon, first passes through 10 cleaning fluid under pressure, thus some of the particles will be loosened or removed before being subjected to the impact from the jets of the nozzles adjacent the end of the friction plates where the felt leaves them.

15 The cleaning operation is rendered still more efficient by causing the jets on the underside of the felt to be intermittently interrupted, whereby a series of impacts are delivered by each jet against the surface of the 20 felt.

While the working face of the felt is that which particularly needs cleaning and is the most difficult to clean, the back or opposite face of the felt belt may also be 25 cleaned by means of jets of cleaning fluid so positioned as to discharge the cleaning fluid against the upper surface of the felt at an acute angle thereto.

After the surface of the felt has been 30 cleaned as hereinbefore set forth, the process contemplates subjecting the felt to suction, causing the same to be deflected or curved downwardly and jets of fluid under pressure are preferably directed against the 35 portion of the felt which is convexly curved and which is being simultaneously subjected to suction, the vena contracta of each jet being at the surface of the felt. This portion of the operation is preferably performed 40 by utilizing a suction box, open at the top, over which the felt travels and into which it is drawn downwardly to a certain extent by the suction in the box, causing the felt to thus assume a downwardly curved or 45 sagging portion. At the bottom of this sagging portion means are supplied for wiping the surface of the felt in order to remove any moisture or particles which the suction upon the felt has not accomplished. 50 There is thus created a suction upon the convexly curved felt as the latter travels along over the suction box, simultaneously the jets play against this convexly curved portion of the felt, and subsequent to the operation 55 of the jets upon the surface of the felt the wiping operation takes place. The means for performing the wiping operation just lightly touches the lowermost part of the convexly curved portion of the felt belt.

60 It will be understood that by thus bending the felt belt while being subjected to suction and causing jets of fluid to be directed against it under pressure, the foreign matter which may remain upon the surface of the 65 belt is removed, and the suction and wiping

process subsequently remove any moisture from the felt belt, thus completing the cleaning operation.

In the following specification three forms of apparatus are disclosed for supplying fluid under pressure to the surface of the belt and holding it against the surface of the belt under pressure and in a restricted area, while the belt travels along in contact with the fluid thus supplied, and preferably in the 75 opposite direction to that in which the fluid is moving.

The preferred form of apparatus for carrying into practical operation my improved felt cleaning process will now be 80 specifically described, but it is to be understood that any mechanical equivalent of the apparatus hereinafter set forth is to be included within the scope of this invention as set forth in the appended claims. 85

The invention consists in an improved process for cleaning felt belts and in an improved mechanism for carrying said process into practical operation, as set forth in this specification and particularly pointed out in 90 the claims.

Referring to the drawings:

Figure 1 represents a plan view of a felt cleaning machine embodying my invention, portions thereof being broken away to save 95 space in the drawings and to more clearly illustrate portions otherwise obscured.

Fig. 2 is an enlarged vertical section taken on the line 2—2 of Figure 1.

Fig. 3 is a detail plan view of the mechanism for locally tensioning the felt and of the mechanism for limiting the lateral spread of the cleaning fluid over the surface of said felt. 100

Fig. 4 is a detail transverse section taken 105 on the line 4—4 of Fig. 3, illustrating the positions of the air nozzles with relation to the felt and to the tensioning plate.

Fig. 5 is a detail section of the fluid guiding plate taken on the line 5—5 of Fig. 3. 110

Fig. 6 is a sectional elevation of a modified form of cleaning apparatus.

Fig. 7 is a sectional elevation of another modified form of cleaning apparatus taken on line 7—7, Fig. 8. 115

Fig. 8 is a plan of the form of cleaner illustrated in Fig. 7.

Like numerals refer to like parts throughout the several views of the drawings.

In the drawings, A represents a felt belt 120 of a paper making machine, said belt travelling in the direction of the arrow a, Fig. 2, the working face of said belt facing downward.

Mounted upon a base 5, which is located 125 beneath the felt A is a carrier 6, constructed in the form of an angle bar and mounted to reciprocate transversely of the direction of feed of the felt A upon a plurality of rollers 7, the latter being rigidly fastened to shafts 130

8 mounted to rotate in bearings 9 provided upon the base 5.

A reciprocating movement is imparted to the carrier 6 by a screw 10 which has screw-threaded engagement with a nut 11 fastened to the underside of the carrier 6. The screw 10 is rotated in opposite directions by means of a reversible driving mechanism 12 located within a casing 13. Any suitable form of reversible driving mechanism may be employed, and said mechanism needs no detailed description. Briefly, however, the mechanism 12 illustrated comprises a driving pulley 14 fast to a shaft 15, and the latter 10 has a sliding clutch member 16 splined thereto and located within the casing 13. The clutch member 16 is provided with sets of clutch teeth 17 and 18 at opposite ends thereof and adapted to engage clutch teeth 19 and 20 provided upon bevel gears 21 and 22 respectively. The gears 21 and 22 are mounted to rotate loosely upon the shaft 15, and said gears each mesh with a bevel gear 23 mounted on a vertical shaft 24, and the former has 25 a worm 25 fast thereto which engages a worm gear 26 fast to the shaft 10.

The clutch member 16 is moved longitudinally upon the shaft 15 in order that it may be engaged with and disengaged from the 30 gears 21 and 22 by a rock shaft 27 which is operatively connected thereto. A rocking motion is imparted to the shaft 27 by an adjustable connecting rod 28, one end of which is operatively connected to said rock shaft, 35 while the other end of said connecting rod is operatively connected to a bell crank lever 29, pivoted at 30 to a bracket 31 fast to the casing 13. The lever 29 is rocked by a bar 32 which is rigidly fastened to the carrier 6. 40 Tappets 33 and 34 are fastened to the bar 32, and said tappets are adapted to engage the opposite sides of an arm of the lever 29, thereby reversing the movement of said lever and the parts connecting the same to the 45 rock shaft 27, and this reversal of movement will cause the clutch member 16 to be operated to reverse the direction of rotation of the shaft 10.

The felt A, while being subjected to a portion of the cleaning instrumentalities, is supported upon a plurality of plates 35, each of which is mounted upon a balanced lever 36 pivoted at 37 on brackets 38, and said plates are yieldingly held against the undersurface 55 of said felt by a weight 39 which is adjustably mounted upon the lever 36. The plates 35 are pivotally mounted at 40 upon the ends of the levers 36 in a manner which will allow them to rock in any direction as the felt 60 passes thereover. Any desired number of the plates 35 may be employed, the same constituting a series extending transversely beneath the felt and the plates being equally spaced apart.

The plates 35 are provided upon their op-

posite longitudinally extending edges with ridges or ribs 35' against which the undersurface of the felt belt rests, and between the ridges 35' and beneath the felt belt 28 is thus formed a chamber 68 through which the fluid is forced under pressure while contacting with the undersurface of the felt belt. 70

Also mounted upon the carrier 6 is a discharge pipe 41 for a washing fluid, such as water, and said pipe extends longitudinally of said carrier 6 and transversely of the felt A, being secured to the carrier 6 by a clamp 42. A plurality of nozzles 43 are formed upon the pipe 41 and said pipe and nozzles are positioned to discharge the washing fluid 75 in jets 44 at a slant against the undersurface of the felt, the fluid striking the felt in an angular space, where a curved edge of said plate meets the undersurface of the felt. The jet of fluid 44, in striking the undersurface 80 of the felt, delivers a blow of sufficient force to discharge from said undersurface all except the most difficult matter to be removed therefrom, and to make the impact as efficient as possible, it is preferable to set the nozzles 43 85 at such a distance from the felt that the vena contracta of the jet is at the face of the felt. The plates 35, by yieldingly engaging the undersurface of the felt, tension the latter at the points where the jets of fluid 44 impinge 90 thereagainst and said fluid is also guided along the undersurface of the felt between the said plates and felt in the chamber 68 and acts to dislodge the matter clinging thereto. The fluid is discharged at the opposite end of the chamber 68 from that at which the nozzles are positioned. The discharge pipe 41 is connected by a hose 45 with any suitable source of fluid supply. 95

Located above the felt A is a series of nozzles 46, which are positioned to discharge 100 cleaning fluid at an angle against the upper surface or back of said felt, jets 47 of said fluid from said nozzle impinging upon said felt at a point nearly opposite that engaged by the under jets 44.

The effect of a cleaning fluid on the upper surface or back of the felt may be increased by intermittently varying the resistance to its passage by means of a corrugated roller 48 located above and adjacent to the felt A and approximately opposite the point at which the jets 44 impinge, the roller 48 being positioned relatively to the upper surface of the felt so as to slightly deflect the felt downwardly. The roller 48 has friction driving discs 49 located at each end thereof, which contact with the upper surface of the felt in a manner to rotate said roller with a peripheral speed equal to that of the speed 115 of the felt. As the roller 48 rotates, the corrugated portions thereof intermittently intercept the fluid and deflect the same, and shake or vibrate the felt, which assists in 120 dislodging the foreign material therefrom. 125

The effectiveness of the lower jets of fluid 44 are increased by means of a corrugated roller 50 which is positioned in the path of said jets between the nozzles 43 and the undersurface of the felt.

It will be understood that the jets of fluid 44, which are delivered against the undersurface of the felt, are themselves interrupted on their passage to the felt by the 10 corrugated roller 50, and that the jets of fluid 47 are directed against the upper surface of the felt without interruption, but the flow of fluid along the upper surface of the felt from said jets is interrupted by the 15 corrugated roller 48.

In order to increase the cleaning action of the fluid for certain classes of work, a jet of steam is preferably employed associated with the plates 35, said steam issuing from 20 the upper surface of said plates through discharge outlets 51 and heating the fluid at that point. Steam is conducted to the plates 35 through a flexible hose 52 from which said steam passes through a passage 53 provided in the plates to the discharge outlets 51.

As an aid in holding the felt against the upper surface of the plates 35 and also in confining the washing fluid to a certain area 30 upon the upper surface of the felt, two rows of air nozzles 54 are provided extending longitudinally of the felt and approximately opposite the longitudinal edges of the plates 35, the air from said nozzles being directed 35 at an angle against the upper surface of said felt.

The other rows of air nozzles 55 are also provided and directed at an incline toward the side edges of the plates 35 beneath the 40 felt, the jets of air pressure assisting in confining the fluid laterally between the upper surface of the support and the undersurface of the felt, and within the chamber 68 while assisting in forcing the current of 45 fluid in the chamber toward the outfall or overflow thereof.

After being subjected to the cleaning instrumentalities hereinbefore mentioned, the 50 felt A is led across the top of a stationary suction box 56 which extends across the entire width of the felt. Inserted in grooves 57 provided in the upper edges of the side walls of the suction box, are glass rods 58 over which the felt A slides with a minimum 55 amount of friction. Another glass rod 59 extends lengthwise of the suction box 56 and is positioned at a lower level than are the rods 58. The rod 59 allows the felt A to sag somewhat into the suction box, and is 60 preferably supported by springs 85 upon brackets 59' adjustably fastened to one side of the suction box 56, so that the rod 59 can be raised and lowered, as may be desired, or the rod may be spring supported and thus 65 self adjusting. In practice, the rod is thus

positioned so as to slightly touch the lowermost convex portion of the belt as it passes over the suction box. The function performed by the rod 59 is that of wiping any moisture off the undersurface of the felt 70 which is not removed by the suction. A pipe 60 connects a suction chamber 61 with any suitable mechanism for creating suction within said chamber.

Extending longitudinally through the suction box 56 is a discharge pipe 62 for washing fluid, and said pipe is provided with a plurality of nozzles 63 which are positioned to discharge said washing fluid in jets 64 against that undersurface of the felt A 80 which is being subjected to the influence of the suction action. The pipe 62 extends through glands 65 in the end walls of the suction box and is fastened to a bracket 66 mounted upon the carrier 6, and the latter 85 imparts a reciprocating movement to the pipe 62 within the suction box, causing the jets of washing fluid 64 to thoroughly wash the undersurface of the felt. The pipe 62 is connected by a flexible hose 67 to the 90 source of fluid supply.

The general operation of the mechanism hereinbefore specifically described is as follows:—The felt A travelling in the direction of the arrow a, Fig. 2, is supported upon 95 the plates 35, which are held in yielding engagement with the undersurface of said felt. As the felt passes over the plates 35, the fluid in the chamber 68 is heated by steam, which is emitted from discharge ports 100 51 provided in said plates. Jets of fluid 44 and 47 are directed against the under and upper surfaces respectively of the felt at an acute angle thereto, and the fluid from the under jets 44 is forced between the undersurface of the felt and the upper surface of the plates 35 in the chamber 68, and the latter acts to guide said fluid between said surfaces, under pressure, thus washing from the felt the majority of particles of foreign 110 matter adhering thereto.

The effect of the jets of fluid 44 and 47 is also increased by intermittently varying the resistance of its passage to or along the felt by means of the corrugated rollers 50 115 and 48, and the jets of fluid in striking the felt cause the same to vibrate and shake off the foreign particles.

The plates 35 not only support the felt but also tension the latter at the location 120 where the jets of fluid impinge against the felt.

Jets of air from the nozzles 54 and 55, above and below the felt, tend to limit the lateral spread of the cleaning fluid over the upper and under surfaces of the felt and hold the felt against the action of the fluid. After passing from the influence of the washing instrumentalities hereinbefore mentioned, the felt passes across the top of the 125

suction box 56, where the undersurface of but it is surrounded or nearly surrounded said felt is subjected to a suction and wiping action tending to dislodge any foreign particles that may still remain upon said undersurface, and as said felt passes across the top of said suction box, it is again engaged by a series of jets of fluid which supplement the suction action in removing the foreign matter. The action of fluid operating in a partial vacuum is very effective in removing foreign matter not possible with other means, the suction holding the felt against the tension exerted by the fluid.

In Fig. 6 a modified form of my invention is illustrated in which 69 is a chamber upon which the felt A is held down by suction supplied through a suction pipe 70 and within which the cleaning fluid is vigorously circulated by means of nozzles 71 and 72 positioned at an acute angle to the undersurface of the felt A and supplied with cleaning fluid under pressure through a pipe 73, so that the cleaning fluid is ejected in a direction opposite to the travel of the felt A, said felt travelling in the direction of the arrow a. The nozzles 71 and 72 are positioned at a short distance below the felt, so that the vena contracta of the jets will be at the lower surface of the felt and will 80 impinge thereon with maximum force.

It will be seen that the stream of fluid from the nozzle 71 impinges on the felt and travels along its surface and tends to support the fluid from the nozzle 72 keeping it in contact with the lower surface of the felt A for a greater distance than would otherwise be the case.

The travel of the fluid is limited by the end of the chamber 69, where it turns downwardly and flows away to the pipe 70. In this construction the whole of the interior of the chamber 69 is kept under suction, the pipe 70 being connected to a suitable suction pump. This suction holds the felt down upon the upper edges of the chamber 69, so that fluid cannot escape beyond the upper edges of the chamber. The action of the fluid is therefore confined to a small portion of the width of the felt belt, just so much as it can efficiently wash. The suction also removes the cleaning fluid with the waste matter which has been detached from the felt before it passes from the chamber.

In Fig. 7 another modified form of my invention is illustrated in which there are two chambers 74 and 75. The chamber 74 contains four inclined nozzles 76, 77, 78 and 79 to which cleaning fluid is supplied under pressure through a pipe 78', the fluid being removed from the chamber 74 by a pipe 74'. The chamber 75 has a single nozzle 80 positioned therein, which is also inclined to the surface of the belt A and cleaning fluid is supplied to the nozzle 80 through a pipe 79'. The chamber 74 is not itself under suction,

but it is surrounded by a channel 81 formed in the wall of the chamber 74, which is connected through narrow passages 82 with the chamber 75. The chamber 75 is joined by means of a pipe 70 83 to a suction pump, not shown in the drawing, by which a fair degree of vacuum is maintained in the chamber 75, say three to five inches as measured by a mercury gauge.

Means 84 are provided for adjusting the area of the passages 82 so that a less degree of vacuum may be maintained in the channel 81, say one to three inches. This arrangement has the advantage that the great bulk of cleaning fluid ejected from the nozzles 76, 77, 78 and 79 is not to be dealt with by the suction pump, but only by a circulating pump, not shown in the drawings, by which it is forwarded through the system, and through the pipes 78' and 74'.

It will be seen that the jets from the nozzles 76, 77 and 78 assist in holding the fluid, which has been directed against the undersurface of the felt belt A, against said undersurface in the same manner as the jet 71 acts with relation to the fluid supplied by the jet 72 in the form of my invention illustrated in Fig. 6.

The embodiments of my invention illustrated in Figs. 6 and 7 thus illustrate a means for directing cleaning fluid against the surface of the felt and means for urging the fluid along the felt and pressing it against the undersurface of the felt. Thus to a certain extent the jet 71 in Fig. 6 and the jets 76, 77 and 78, Fig. 7, perform the function of the plates 35 in that embodiment of my invention illustrated in Figs. 1 to 5 inclusive.

I claim:

1. That step in the process of cleaning a tensioned moving felt belt which consists in simultaneously subjecting a given area of the same surface of the felt to suction and to impact from a jet of fluid in the suction zone.
2. A machine for cleaning a felt belt embodying therein means to direct a jet of cleaning fluid along the surface of said felt and means to confine the fluid so directed within a predetermined portion of said surface.
3. A machine for cleaning a felt belt embodying therein means to direct cleaning fluid along a surface of said felt and means for maintaining it in contact therewith.
4. A machine for cleaning a felt belt comprising, in combination, means to support said felt, and means to direct a jet of cleaning fluid along the surface of said felt between said support and said felt.
5. A machine for cleaning a felt belt comprising, in combination, means to direct a jet of cleaning fluid along the surface of said felt, means to maintain said fluid in

contact with the felt and means to tension said felt at the location where said fluid is so maintained.

6. A machine for cleaning a felt belt comprising, in combination, a plate supported in contact with a face of said felt, and means to direct a jet of cleaning fluid along the surface of said felt between said surface and said plate.

10 7. A machine for cleaning a felt belt comprising, in combination, a plate supported in contact with a face of said belt and provided with a chamber extended longitudinally thereof, open at the top and opposite

15 ends to allow a body of cleaning fluid to be directed along said chamber in contact with a surface of said felt.

8. A machine for cleaning a felt belt comprising, in combination, a plate with oppo-

20 sitely disposed ridges extending longitudinally thereof and spaced apart to form a chamber in its upper surface, said plate being supported in contact with a face of said felt to allow a body of cleaning fluid

25 to be directed along said chamber in contact with said felt.

9. A machine for cleaning a felt belt comprising, in combination, means to support

30 said felt, means to direct a jet of cleaning fluid along the surface of said felt between said support and said felt, and means to intermittently interrupt the direct passage of said jet of cleaning fluid to said felt.

10. A machine for cleaning a felt belt comprising, in combination, means to support

35 said felt, means to direct a jet of cleaning fluid against the surface of said felt, and means to intermittently interrupt the direct passage of said fluid along said felt.

40 11. A machine for cleaning a felt belt comprising, in combination, means to support said felt, means to direct a jet of cleaning fluid along the surface of said felt between said support and said felt, and means to

45 limit the lateral spread of said cleaning fluid over the surface of said felt.

12. A machine for cleaning a felt belt comprising, in combination, means to support said felt, means to direct a jet of cleaning fluid

50 along the surface of said felt between said support and said felt, and suction cleaning means also acting upon the surface of said felt.

13. A machine for cleaning a felt belt comprising, in combination, a reciprocating carrier, means upon said carrier to support

55 said felt, and means also located upon said carrier to direct a jet of cleaning fluid along the surface of said felt between said support and said felt.

14. A machine for cleaning a felt belt comprising, in combination, a reciprocating carrier, means upon said carrier to support

60 said felt, means also located upon said carrier to direct a jet of cleaning fluid along the

surface of said felt between said support and said felt, means associated with said support to direct steam into said fluid, and suction cleaning means also acting upon the surface of said felt.

15. A machine for cleaning a felt belt comprising, in combination, a plate yieldingly contacting with a surface of said felt, mechanical means to vary the pressure of said plate upon said felt, and means to direct a jet of cleaning fluid along the surface of said felt between said surface and said plate.

16. A machine for cleaning a felt belt comprising, in combination, a plate yieldingly contacting with a surface of said felt, mechanical means to vary the pressure of said plate upon said felt, means to direct a jet of cleaning fluid along the surface of said felt between said surface and said plate, and means to limit the lateral spread of said cleaning fluid over the surface of said felt.

17. A machine for cleaning a felt belt comprising, in combination, a plate yieldingly contacting with a surface of said felt, means to vary the pressure of said plate upon said felt, means to direct a jet of cleaning fluid along the surface of said felt between said surface and said plate, and means to intermittently interrupt the direct passage of said jet of cleaning fluid to said felt.

18. A machine for cleaning a felt belt comprising, in combination, a plate yieldingly contacting with a surface of said felt, mechanical means to vary the pressure of said plate upon said felt, means to direct a jet of cleaning fluid along the surface of said felt between said surface and said plate, means to limit the lateral spread of said cleaning fluid over the surface of said felt, and suction means for cleaning the surface of said felt.

19. A machine for cleaning a felt belt comprising, in combination, a plate supported in contact with the undersurface of said felt, means to direct a jet of cleaning fluid along the undersurface of said felt between said surface and said plate, and means to direct another jet of cleaning fluid against the upper surface of said felt and at an angle thereto.

20. A machine for cleaning a felt belt comprising, in combination, a plate supported in contact with the undersurface of said felt, means to direct a jet of cleaning fluid along the undersurface of said felt between said surface and said plate, means to intermittently interrupt the direct passage of said jet of cleaning fluid to said felt, means to direct another jet of cleaning fluid against the upper surface of said felt at an angle thereto, and means to intermittently interrupt the passage of the fluid from said last-named jet along said felt.

21. A machine for cleaning a felt belt comprising, in combination, a reciprocatory

carrier, a conductor for cleaning fluid mounted upon said carrier and adapted to direct a plurality of jets of said fluid against said felt, and means to tension said felt at each of the locations where said jets of cleaning fluid impinge thereagainst.

22. A machine for cleaning felt comprising, in combination, means to support a felt belt, means to direct a jet of cleaning fluid along the surface of said felt between said support and said felt, and means to discharge a plurality of air jets extending longitudinally of said felt upon opposite sides of said support at an angle to said felt, thereby limiting the lateral spread of said cleaning fluid over the surface of said felt.

23. A machine for cleaning a felt belt comprising, in combination, a plate supported in contact with the undersurface of said felt, means to direct a jet of cleaning fluid along the undersurface of said felt between said undersurface and said plate, means to intermittently interrupt the direct passage of said jet of cleaning fluid to said felt, means to direct another jet of cleaning fluid against the upper surface of said felt at an angle thereto, and means to intermittently interrupt the passage of fluid from said last-named jet along said felt, and means to discharge a plurality of air jets located above and below said felt and positioned longitudinally thereof at an angle to said felt.

24. A machine for cleaning a felt belt comprising, in combination, means to support said felt, means to direct a jet of cleaning fluid along the surface of said felt between said support and said felt, and a corrugated roller extending transversely of said felt and positioned in the path of the jet of cleaning fluid to intermittently intercept the direct passage of said fluid to said felt.

25. A machine for cleaning a felt belt comprising, in combination, a carrier, means to impart a reciprocatory movement thereto, a conductor for a cleaning fluid mounted upon said carrier and adapted to discharge a plurality of jets of fluid against said felt, means to tension said felt at each of the locations where said jets of cleaning fluid impinge thereagainst, and suction means also acting upon a surface of said felt.

26. A machine for cleaning a felt belt comprising, in combination, a carrier, means to impart a reciprocatory movement thereto, a conductor for a cleaning fluid mounted upon said carrier and adapted to discharge a plurality of jets of said fluid against said felt, means to tension said felt at each of the locations where said jets of cleaning fluid impinge thereagainst, suction means also acting upon a surface of said felt, and means to discharge cleaning fluid against the surface of said felt acted upon by said suction means.

27. A machine for cleaning a felt belt comprising, in combination, a carrier, means to impart a reciprocatory movement thereto, a conductor for a cleaning fluid mounted upon said carrier and adapted to discharge a plurality of jets of said fluid against said felt, means to tension said felt at each of the locations where said jets of cleaning fluid impinge thereagainst, a suction box over which said felt is fed, and a conductor for cleaning fluid within said box and discharging cleaning fluid against said felt as it passes across the top of said box.

28. A machine for cleaning a felt belt comprising, in combination, a carrier, means to impart a reciprocatory movement thereto, a conductor for a cleaning fluid mounted upon said carrier and adapted to discharge a plurality of jets of said fluid against said felt, means to intermittently interrupt the direct passage of said jets of cleaning fluid to said felt, means to tension said felt at each of the locations where said jets of cleaning fluid impinge thereagainst, suction means also acting upon a surface of said felt, and means to discharge cleaning fluid against the surface of said felt acted upon by said suction means.

29. A machine for cleaning a felt belt comprising, in combination, a carrier, means to impart a reciprocatory movement thereto, a conductor for a cleaning fluid mounted upon said carrier and adapted to discharge a plurality of jets of said fluid against said felt, means to intermittently interrupt the passage of the fluid from said jets along said felt, means to tension said felt at each of the locations where said jets of cleaning fluid impinge thereagainst, suction means also acting upon a surface of said felt, and means to discharge cleaning fluid against the surface of said felt acted upon by said suction means.

30. A machine for cleaning a felt belt comprising, in combination, a carrier, means to impart a reciprocatory movement thereto, a conductor for a cleaning fluid mounted upon said carrier and adapted to discharge a plurality of jets of said fluid against said felt, means to intermittently interrupt the passage of fluid from said jets along said felt, means to limit the lateral spread of said cleaning fluid over the surface of said felt, means to tension said felt at each of the locations where said jets of cleaning fluid impinge thereagainst, suction means also acting upon a surface of said felt, and means to discharge cleaning fluid against the surface of said felt acted upon by said suction means.

31. A machine for cleaning a felt belt comprising, in combination, a carrier, means to impart a reciprocatory movement thereto, a conductor for a cleaning fluid mounted upon said carrier and adapted to

- discharge a plurality of jets of said fluid against said felt, means to intermittently interrupt the passage of fluid from said jets along said felt, means to limit the lateral 5 spread of said cleaning fluid over the surface of said felt, means to tension said felt at each of the locations where said jets of cleaning fluid impinge thereagainst, suction means also acting upon a surface of said 10 felt, and means to discharge cleaning fluid against the surface of said felt acted upon by said suction means.
32. A machine for cleaning a felt belt embodying therein means to direct an intermittently interrupted travelling jet of cleaning fluid against said felt. 15
33. A machine for cleaning a felt belt embodying therein means to direct a travelling jet of fluid against said felt, and means to intermittently interrupt the flow of said fluid 20 along the surface of said felt.

In testimony whereof I have hereunto set my hand.

FREDERICK W. VICKERY.
